UNITED STATES PATENT OFFICE

96,617

DESIGN FOR A SHOE

Philip Lorman, New York, N. Y.

Application July 17, 1935, Serial No. 57,680

Term of patent 3½ years

To all whom it may concern:

Be it known that I, Philip Lorman, a citizen of the United States, residing in New York, in the county of New York and State of New York, have invented a new, original, and ornamental Design for a Shoe, of which the following is a specification, reference being had to the accompanying drawing, forming a part thereof, in which

Fig. 1 is a plan view of a shoe showing my design; and

Fig. 2 is a view in side elevation of the shoe the heel being conventionally represented in dot and dash lines.

I claim:

The ornamental design for a shoe substantially as shown and described.

In testimony whereof, I have affixed my signature hereto.

PHILIP LORMAN.
